UNITED STATES PATENT OFFICE.

ARTHUR W. LE BOEUF, OF BROOKLYN, NEW YORK, ASSIGNOR, BY MESNE ASSIGNMENTS, TO NORTHBORO BRUSH COMPANY, OF NORTHBORO, MASSACHUSETTS, A CORPORATION OF MASSACHUSETTS.

BRUSH MACHINE.

Original application filed May 22, 1916, Serial No. 99,100. Divided and this application filed January 2, 1923. Serial No. 610,124.

This is a division of my original Patent No. 1,449,424 granted Mar. 27, 1923, on an application originally filed May 22, 1916, Serial No. 99,100. This invention relates to 5 an automatic machine for manufacturing brushes. The principal objects of the invention are to provide a machine of compact form so that the various parts thereof can be mounted on a small frame and take up very little 10 space; which will be capable of manufacturing brushes automatically; that is, taking the bristles from a hopper and feeding them automatically through the machine and applying them to brush handles or backs which 15 are previously formed outside of this machine, but which are drilled and tufted on the machine; to provide for taking the tuft from the tuft-forming mechanism and transferring it to a mechanism for setting the tufts in the brush handles; to provide important features of the said transferring mechanism to cause it to perform its functions; to provide an improved brush-making 20 mechanism in which the brush blanks or handles are automatically fed to an intermittently revolving turret which first turns them to a position in which holes are drilled for receiving the tufts, said holes passing 25 only part way through the brush blank, and then feeds them to a substantially opposite position at which the tufts are inserted in the holes previously formed; to provide improvements in the mechanism for operating 30 the said blank-holding turret, in the mechanism by which the drilling and tufting is performed on the blank while held thereon, in the mechanism by which the blanks are held in the turret and discharged therefrom; 35 in the means for feeding the blanks automatically to the turret and clamping them thereon; and to provide improvements in means for operating and co-ordinating the various parts of the mechanism as above described and in the various details and combinations thereof. Further objects and advantages of the invention will appear hereinafter.

Reference is to be had to the accompanying drawings in which

Fig. 1 is a sectional view showing the

brush blank and illustrating the application of the tuft thereto;

Fig. 2 is a transverse sectional view of the same;

Fig. 3 is a rear elevation of the machine showing the parts for supporting the brush blanks and operating them and also showing the transferring device;

Fig. 4 is a sectional view on the line 4—4 of Fig. 3;

Fig. 5 is an end elevation on enlarged scale of the index clutch shaft for the handle turret;

Fig. 6 is a plan of the clutch locking mechanism thereof;

Fig. 7 is a sectional view on the line 7—7 of Fig. 8;

Fig. 8 is a rear elevation of the clutch operating mechanism thereof;

Fig. 9 is a sectional view on the line 9—9 of Fig. 4;

Fig. 10 is a perspective view of the universal joint in the index clutch shaft;

Fig. 11 is a face view of the crosswise brush feed cam and connected parts;

Fig. 12 is an edge view of the same;

Fig. 13 is a rear face view of the longitudinal feed cam;

Fig. 14 is a plan of the same;

Fig. 15 is a similar view of a portion of the parts shown in Fig. 13 but illustrated in different position;

Fig. 16 is a plan of the brush blank showing one way in which the tufts can be set by this machine;

Fig. 17 is a plan of the handle turret showing connected parts, with parts in section;

Fig. 18 is an end view of the same showing the shaft in section;

Fig. 19 is a side elevation of the brush blank holding jaws;

Fig. 20 is a plan of the same showing the index gear;

Fig. 21 is a sectional view on the line 21—21 of Fig. 19;

Fig. 22 is a rear view of the hopper and ejector mechanism with the parts in the same position as in Fig. 3;

Fig. 23 is a plan view of part of the driving mechanism therefor;

Fig. 24 is a sectional view on the line 24—24 of Fig. 23;

Fig. 25 is an elevation looking in the direction of the arrow in Fig. 23 showing the 5 clutch;

Fig. 26 is a view of one of the clutch members;

Fig. 27 is an elevation of a portion of the 10 handle hopper mechanism looking in the direction of the arrow 27 in Fig. 22;

Fig. 28 is an opposite elevation looking in the direction of the arrow 28 in Fig. 22;

Fig. 29 is a similar view on enlarged scale 15 showing the parts in the position assumed after the delivery of a brush handle;

Fig. 30 is a sectional view on the line 30—30 of Fig. 29;

Fig. 31 is a plan of the end of the pusher;

Fig. 32 is an elevation on enlarged scale 20 of the feed finger pawl showing it in the same position as in Fig. 28;

Fig. 33 is an end elevation of the same;

Fig. 34 is an elevation of the ejector mechanism looking in the direction of the arrow 25 34 in Fig. 22;

Fig. 35 is a similar view showing the parts in different positions; and

Fig. 36 is an edge elevation of the same.

The invention is illustrated in the form 39 of a machine for making tooth brushes in which a base is provided for supporting a main frame of the machine. The motive power for the machine is preferably obtained from a motor 105 which by a belt drive shaft 106. This shaft by worm 107 and worm-wheel 108 drives what I call the main shaft 109 running longitudinally of the machine. This shaft operates most of the mechanism connected with the making of the tufts.

40 As has been stated the tufts are formed by forcing bunches of bristles into metallic cups. It has been described in my above mentioned patent how the tuft of bristles with its metallic cup is cut off and left in

45 position to be removed from the tuft making mechanism. For the purpose of transferring the tuft a transfer cam 00 oscillates a transfer frame 3 about a shaft 4, arranged longitudinally on the main frame. This

50 frame 3 is provided near its outer end with a longitudinal shaft 298 having a fixed head 299 carrying a fixed thin jaw plate 5. This jaw plate has a curved edge. Mounted on an oscillating stud carried by this head

55 299 is a corresponding movable jaw plate 8 having a curved edge. These two edges co-operate with each other to form jaws for engaging the tuft of bristles B. This frame is designed to oscillate about its shaft from the position in which the axis of the passage between the curved edges of the two jaws is in line with the axis of the bristle tuft as it is being cut off the wire. Here

60 a cam 295 on the shaft 298 engages a pin 296 to hold the shaft in proper position.

The jaws first come to the position in which a tail 9 connected with the movable jaw 8 is still in contact with a pivoted latch 10. Just as soon as this tail 9 passes over the end of this latch 10, a spring forces the 70 jaw closed. This grips the tuft of bristles as stated so that it can be moved away from the turret mechanism after having been cut off.

75 The frame swings down to the position in which the cam 295 engages a stop to hold the jaws vertical. During this motion downwardly the position of the jaws is changed. The shaft 298 on which is carried the so-called fixed jaw 5 is caused to swing to a 80 certain position by a spring 16 connected to the jaw at one end and with a hub in which the shaft has a bearing at the other. This spring holds the shaft back and also holds it against rotation beyond a certain point. This results in sliding the shaft 298 longitudinally and moving the jaws 5 and 8 about this shaft as a center so as to bring these flat jaws into a position such that they move edgewise with the oscillation of 85 this frame. The edge of the metallic cup is spaced slightly from the jaws and when the jaws move forward in the manner just described, the cup is intended to enter a hole in a brush blank C and the jaws then engaging the edge of the cup positively force the same in so as to insert it and cause it to be held frictionally therein.

90 The spring 16 acts to force the shaft 298 back. This withdraws the jaws from the tuft of bristles set in the brush back and leaves the frame in a position to rise about its shaft at the next oscillation produced by its cam. This transferring mechanism is 95 not shown or claimed herein as it is fully shown and claimed in said original patent. It may be regarded as a means for feeding the tufts to the brush blank and setting them therein.

100 Fig. 1 shows the jaws pushing the cup 110 into the brush blank and Fig. 2 shows the position of the parts when completed. This completes the operation of setting a single tuft of bristles in a brush blank and I will now proceed to describe mechanism for manipulating the blank itself.

Brush turret driving and indexing mechanism.

110 On the shaft or rod 24 is oscillatably journaled a frame 41 which is provided with forked bearings for that purpose. The slight oscillation which this frame has up and down will be referred to later. It will 115 be seen that the shaft 109 by means of bevel gears drives a transverse shaft 50 which is a drive shaft for this part of the mechanism. On this shaft is fast a gear 51 which meshes with a loose gear 52 rotatable on the transverse index clutch shaft 53. This shaft con- 120

125

130

sists of two parts connected by a flexible joint 56. It is on this shaft that is located a sliding keyed pinion 54 meshing with the turret index gear 116. A spring-pressed 5 clutch member 55 is arranged to transmit power from the gear 52 to this shaft 53 and thus rotate the turret. For the purpose of operating this clutch the shaft 58 is oscillated intermittently by means to be described below. Fixed on this shaft is an arm 59 which is provided with a roll 60 entering the groove 61 in the clutch member 55. Normally the spring would hold the clutch member closed, but when this roll moves into the end of the groove it draws the clutch member away and stops the rotation of the shaft 53. The shaft remains stopped, of course, until the shaft 58 is moved to withdraw the roller from position. A spring 62 (Fig. 7) keeps the roller in engagement with the clutch member so that it will automatically move into this groove when the same has nearly completed a revolution.

Loosely mounted on the shaft 58 is a locking arm 63 which, when the arm 59 is drawn back, is moved with it on account of a projection 64 on the latter extending behind the arm 63. A spring 65 (Fig. 7) acts constantly to pull this arm toward the clutch so that when it is allowed to move in that direction by the arm 59 a wedge-shaped projection 66 on the back of the locking arm will engage in a longitudinal groove 67 in the clutch member 55. The object of this is to provide for positively stopping the rotation of the clutch member just at the end of a complete revolution so that the index clutch shaft 53 can rotate just once and then be forced to stop exactly on the right point.

On the shaft 50 there is a cam 70 which operates a cam roller 71 on a lever 69 freely swinging on the shaft 58. By means of an adjustable link 72 this lever is adjustably connected with a pawl lever 73 freely pivoted on a transverse shaft 74. This lever carries a spring-pressed pawl 75 adapted to engage ratchet teeth on a wheel 76 fixed on the shaft 74. For each oscillation of this lever the wheel 76 will be advanced one step, which according to the adjustment will be the length of one tooth or a greater number as may be desired. In the form herein shown there are forty-seven of these teeth on the wheel and the wheel operates the width of one tooth at each operation.

Rotating with the shaft 74 is a clutch operating dog 77 which engages an arm 78 fixed to the shaft 58 and operates that to stop the rotation of the turret at the end of each complete rotation of the shaft 74.

Longitudinal turret motion.

Secured on this shaft 74 is a lengthwise cam 80. This cam is provided with an intermittent spiral groove 81 for receiving and

controlling a roll 82 mounted on the end of a lever 83. It will be obvious that the rotation of this cam will cause this roll to be moved step by step farther from the center of the shaft 74 and the lever to be moved outwardly, intermittently. There are sixteen steps or motions to this cam and it takes three oscillations of the lever 73 and the advance of the wheel 76 three steps to move the roller 82 from one level to the next one in the form shown. The operation of the lever 83 in this manner turns a shaft 84 by means of adjustable studs 85 on the lever and a plate 89 on the shaft. A lever 86 on the shaft 84 is thus moved. On this is mounted a pin yoke 87 having pins engaging between two flanges of a flanged wheel 88 located on opposite sides of the pinion 54 on the shaft 53. These flanges engage the opposite sides of the brush turret index gear 116 and cause it together with the whole turret, involving the parts 158 and 159 and the jaws 161 and 162 carried thereby to move along a shaft 111 on which they are rotatably mounted this shaft being stationary. The sleeve 110 moves with them. The cam 170 has a slot 169 through which the end of the arm 171 moves at this time.

At the end of the spiral groove the roll 82 enters a notch in the end of a pawl 90. This pawl is provided with a long slot 91 through which it is pivoted on a screw 92 carried by the cam and is normally held in the position shown in Fig. 13 by a spring 93. Just behind the rear edge of this pawl is a spring-pressed latch stop 94. As the cam rotates in the direction indicated the roller 82 will come out until, in the present instance at the 47th position, it enters this notch in the pawl 90 and presses the whole pawl backwardly until the end of the pawl snaps over the latch 94 and allows the parts to move to the position shown in Fig. 15 so as to drop the roll 82 back into its first position. The pressure being removed from the pawl it then snaps back into the position shown in Fig. 13. This mechanism is for the purpose of feeding the brush turret longitudinally by a step-by-step motion into sixteen different positions. It will be understood that in each one of these positions certain operations are performed on the brush blank as will appear below.

Vertical turret motion.

This part of the mechanism if used alone would merely provide one line of holes or tufts in the brush, but the machine is designed and shown in these drawings is adapted to place three lines of bristle tufts and two extra ones at the end making forty-seven in all. In order to accomplish this the shaft 74 is provided with a cross-wise cam 95. This is fixed to the shaft and is provided with forty-seven steps thereon. These

are divided into fifteen series of three steps each, a low, an intermediate, and a high step in each case, and two additional steps constituting the last and next to the last in the series, but, of course the arrangement would be different if a different number of tufts were to be set in the brush. These steps are indicated by the numerals 1, 2, 3, 4, 46 and 47. It will be understood that 10 while the roller 82 is moving along one concentric surface during the three advancing steps of the shaft, the roller 96 which rests on the cam 95 will be lowered from a high step to an intermediate one, and then to the 15 low step of that series.

The effect of this roller is as follows: It is mounted on a member 97 which is forked at the bottom to guide it about the shaft 74 and at its upper end a rod 98 connected 20 with it vertically reciprocates a rest 99 on the top of said rod on which the frame 41 rests, and consequently it raises and lowers that frame about its pivot shaft 24 with all the parts supported upon it. Starting from 25 the position marked "1" in Fig. 16, when the roller 82 is in the position shown in full lines in Fig. 13, the roller 96 is on the first of the high surfaces 1 of the cam 95. The brush blanks held by the turret will be located in a position which may be represented 30 by the numeral 1 and operated on as will appear. As the wheel 76 moves through the space of one tooth the roller 96 is lowered down on the intermediate surface 2, and the 35 brush blank brought to the position marked "2." Then it is let down into the first low surface 3 and the brush blank brought to the position marked "3." On the next surface which moves the brush turret and the blank along to the next column of figures 40 and the roller 96 rises on the next hinge surface 4 so as to bring the brush blank to the position "4."

Drilling brush blank.

The first operation performed during this motion of the brush blank is the drilling operation. While this is taking place the blank is in the position marked "drill." 50 The lever 69 which is oscillatably mounted on the shaft 58 is connected with a link 100 and through a lever 101 on a bracket 102 reciprocates a drill head 103 to cause the drill to advance and drill a hole at each one of the different positions marked. This drill head is operated from the shaft by means of a pulley 104 and belt.

It is also during this motion that the tufts are set in a blank in the opposite position, 60 namely, the position marked "fill." This has been described as operated from the shaft 109 by cams.

Hopper mechanism.

65 The gear 51 is in mesh with a gear 119

which drives a gear 120 loose on the cam shaft 121 for controlling the handle mechanism. On this shaft there is a spring-pressed sliding member 122 adapted to be operated by a lever 123 pivoted on a stud 124 and having a pin 125 operated by a cam 126 on the shaft 58. This pin 125 is made adjustable in a slot and secured in adjusted position by a set screw 127. The other arm of the lever 123 is provided with a stud or roll 128 entering a groove in the sliding clutch member 122 for the purpose of moving it. This groove is to offset at the end and the clutch member works in the same way as the clutch member 155, that is, the clutch is automatically opened at the end of a revolution. In order to insure that this shaft 121 shall rotate exactly one revolution the clutch member 122 is provided with a groove 129 and on the lever 123 is a spring-pressed pawl 130 for entering said groove and stopping the clutch member and therefore the shaft exactly at the end of the revolution.

On this shaft 121 is a cam 131 which controls a roll 132 on a link 133. This link is bifurcated at its end to form a support and guide on the shaft 121 and at the other end it is connected with a lever 134 which is pivoted at 135 to the end of the frame 41. The other end of this lever above is pivoted to the handle hopper 136. Obviously the motion of the roller 132 out and in with relation to the shaft 121 reciprocates the link 133 and oscillates the lever 134 so as to move the hopper back and forth to bring it into registration with the brush handle turret for delivery thereto.

The hopper has an inclined back plate against which the blanks rest. It is controlled by two angular end plates 137, each held in position by adjustable brackets 138 supported by the hopper itself. The brush blanks can be piled up in the hopper and fed down by gravity. If desired, a weight 110 can be applied to them to insure their proper feeding, but it is not shown herein as it is not a necessary part of the machine.

Also mounted on this shaft 121 is a feed and ejector cam 140 operating a roll 141 on a lever 142 pivoted on the shaft 58. This lever is provided with a lost motion connection with an adjustable rod 143 which in turn is pivoted to an adjustable member 144 carried by a lever 145 pivoted on the back 115 of the hopper 136. This lever is connected at its lower end by a link 146 with a horizontal slide or plunger 147 having a plate 148 for supporting, parallel with it and spaced from it, a rigid pusher 149. The 120 movement of the roll 141 out and in with relation to the shaft 121 reciprocates the link 143, with a lost motion at the end of the stroke, swings the lever 145 and reciprocates the plunger and pusher so as to 125 130

move the plunger along on a guide 139 at the bottom of the hopper 136.

Mounted on the end of the plunger or slide 147 is a rod 150 having on the end thereof adjustable nuts 151 constituting a stop. On the hopper is pivoted a feed finger pawl 152 having a projecting end 153 adapted to project in under the bottom of the hopper to support the end of the next to the lowest tooth brush blank or handle C. The lowest one is supported at this time by a plate 157 so as to project over the brush turret. A spring 154 normally holds this pawl up in the position shown in Fig. 29, the rod 150 passing through a notch 155 therein. When the parts are in the position shown in Figs. 28 and 32 the stop 151 has forced this pawl over to the left to move the lowest blank to the left and hold the rest of the blanks in the hopper as indicated. As soon as the plunger moves to the right far enough to allow the stop 151 to release the pawl 152 the latter moves over to the position shown in Fig. 29, being stopped by a flat surface 156 at the end of the pawl. This allows the pile of brush blanks to drop down as indicated in this figure when the plunger moves over. It will be understood that at the moment of feeding the whole hopper is moved over by the action of the cam 131 to register with the brush turret which will now be described.

Brush clamping jaws.

The frame 41 is provided with bearings which support the hollow non-rotatable but slidable sleeve 110 and the non-rotatable brush turret index shaft 111 which enters the end of the sleeve and has a bearing in it. The shaft 111 has rotatable on it the turret index wheel 116 in the form of a gear driven by the sliding pinion 54 on the shaft 53 and having a hub 158 secured to it. Spaced from this is a plate 159, and these parts together with certain others to be described, constitute the brush holding turret. Journalled in the hub 158 and the plate 159 are a plurality of parallel studs or shafts 160, six being shown in the present instance. Extending out substantially radially from each of these and held against the plate 159 are the same number of stationary jaws 161. These, of course, rotate with the turret head and form a part thereof. Pivotally mounted on the shafts 160 are corresponding movable jaws 162. Springs 163 normally force the movable jaw inwardly against a sliding wedge 164 which is located between each pair of jaws. These jaws are provided with inwardly extending projections 165 on the edge adapted to engage the brush blanks C and hold them in position.

For the purpose of operating the movable jaws to permit them to receive and discharge the brush blanks the following mech-

anism is provided. The shaft 121 is provided with a wedge cam 170 operating an arm 171 on a vertical shaft 172. This cam has a radial slot 169 to permit the end of the arm 171 to move through when the turret moves in one direction as has appeared. A spring 173 is provided for holding this this arm against the cam surface and the shaft has another arm 174 at its upper end. This by means of a pin-and-slot connection 75 operates a lever 175 pivoted on the frame 41 which reciprocates a rod 176 extending axially through the sleeve 110 so as to engage and reciprocate a slide 178. This slide is provided with a pair of projections 179 80 operating the wedge 164. This wedge is provided with a plurality of slanting slots 180 engaging operating pins 181 carried by the several stationary jaws 161. As the wedge is pushed inwardly toward the wheel 85 116 by the projection 179 the wedge is raised between the jaws so as to clamp the brush back under the projections 165. At the same time a wedge-shaped end 182 on the wedge 164 moves outwardly beyond the end 90 of the movable jaw 162 as shown in Fig. 20 and allows the spring to close that jaw. The wedge is forced out substantially into contact with the wheel 116 at its end.

As the operation of depositing a brush blank in the turret has been described in a general way, it is sufficient to say that by the reciprocation to the right of the plunger 147 the pusher 149 forces the lowest blank C in the hopper out of the hopper under the feed finger pawl 152, and the pusher moves the blank up against an adjustable stop screw 184 on the wheel 116. The parts then move back into the position shown in Fig. 29. The pawl 152 allows another blank to drop down on the plate 157 and at the end of the reverse motion the end of the pawl 152 forces the lowest blank C into the position shown in Fig. 28. Before this has been accomplished the projection 179 has been 110 drawn back so that the wedge 182 forces the movable jaw to the right and opens it and the wedge 164 is lowered between the jaws. This leaves the jaws in proper position to receive the blank. Thereafter the wedge is 115 moved in the opposite direction to the position shown in full lines in Figs 20 and 21. The movable jaw closes and the wedge rises so that the blank is clamped in the turret.

Ejector mechanism.

I will now describe the closely related mechanism for ejecting the brush blank from the turret. The position in which the blank is fed is indicated by the word "Feed" 125 in Fig. 18 and the ejecting position by the word "Eject" in that figure. Referring now again to Fig. 22 it will be seen that the lever 142 operates a substantially vertical rod 190 adjustably connected with an arm 130

191 on a shaft 192 carried by a stationary ejector frame 193 on the frame 41. This shaft has another arm 194 which is connected by a link 195 with an arm 196 on a shaft 197 which has a slotted arm 198 engaging a pin 199 on an ejecting hook 200. This hook is mounted on a slide 201 movable in ways on the frame 193. This ejector arm 200 oscillates from the position shown in Fig. 34 to that shown in Fig. 35 where the end of the hook passes down behind the end of the brush blank ready to draw it out of the turret on the backward movement of the slide 201. It will be noticed that just previously the wedge 164 has just been operated to release the brush blank, the two positions of the wedge being clearly indicated in Figs. 34 and 35.

The slide 201 itself is operated by these arms and links 194, 195, and 196. The motion of the arm 194 in the direction of the arrow in Fig. 34 causes the slide to move back away from the stop 202 to the left taking with it, of course, the hook and brush handle and ejecting the same into a hopper or other receiving means as desired. A stop 203 is provided for limiting the downward motion of the ejector hook.

Operation.

The operation of the machine is as follows: The transferring means takes the cup and delivers it to the mechanism for applying the bristle-filled cups to the brush blank. The transferring device swings up into position to engage the bristles and prevent the tuft falling away and at the same time hold it on the transferring device. The details of the operation of this transfferer having been described in connection with the original patent this operation will not be repeated here, but it is sufficient to say that the transfferer, having grasped the tuft beyond its metallic cap, swings over through a considerable arc into a substantially horizontal position from which the tuft is applied to the brush handle or blank under pressure and left secured therein by friction.

The operation on the brush blank is as follows: These blanks, having been previously formed to the proper length and other outside dimensions, are placed in the brush blank hopper. During each complete operation of this machine this hopper is reciprocated and the lower blank discharged therefrom on one of the faces of the brush blank turret. The blank is left on the turret in the proper position and one of the spring gripping jaws thereon engages the blank and holds it in its proper relative position to the turret. The wedge also moves to receive it in place. The turret is then indexed around one step which brings another face into position to receive another

blank. The motions of the turret to bring the brush blank into position for drilling have been described above and it is sufficient to say here that these motions are both circumferential and longitudinal and that in the present design there are three circumferential motions, thus providing for the drilling of three rows of holes, and that the longitudinal motion shifts the blank along step by step. The last row of two holes is provided for by the shape of the cam as stated. This particular design can be varied of course simply by changing the cams which control the two motions of the turret. The brush blank having passed through all these motions and the desired number of holes having been drilled, the turret indexes around again through two idle positions while two other blanks are being drilled and then comes up to the fifth position in which it is directly opposite the drilling position and at that time the tufts are supplied from the transferring devices in proper order and inserted in the holes in the blank in the same order in which the holes are being drilled in a fresh blank oppositely located. The operation of the turret to bring it to the drilling positions also serves to bring this blank to the proper positions for tufting. The tufts having been applied and forced into the holes by the mechanism which has been described, the turret is again indexed around to the sixth position where the ejector engages the new completed brush and forces it longitudinally out of the spring clamp, which has held it, into a hopper, conveyor or any other receiving means (not shown).

It will be seen therefore that this machine is entirely automatic, taking the tufts of bristles and previously formed brush blanks at different points, drilling the holes in the blanks, and forcing the tufts into the holes thus formed so as to produce the complete brush which needs only to have the bristles trimmed down to the proper length after it leaves the machine. All the parts are conveyed from one position to another in the machine automatically and there is no need for any expert oversight of the operations. Practically all that the operator has to do is to see that the machine is running, and to see that it is properly supplied with the three kinds of raw products which it uses.

The strictly metal working mechanism by itself and the tuft forming and setting mechanism by itself are not claimed herein independently of other features of the machine as they form the subject matter of two divisional applications previously filed.

Although I have illustrated and described only a single embodiment of the invention and shown it as applied to a definite character of brush I am aware of the fact that many modifications can be made in the de-

tails of construction and combinations of parts of the mechanism and that it can be applied to the manufacture of other types of brushes without departing from the scope of the invention as expressed in the claims.

Therefore I do not wish to be limited in these respects, but what I do claim is:—

1. In a brush making machine, the combination of a brush turret for supporting brush blanks, means for moving said turret up and down, means for moving the turret longitudinally, and means for intermittently rotating the turret, with means for drilling a hole in the brush blank on one side of the turret in each position, and means for setting a tuft of bristles in the brush blank when in a diametrically opposite position.

2. In a brush making machine, the combination of a frame pivoted to swing on a horizontal axis located at one extreme side thereof, a turret for holding brush backs or the like movably mounted on said frame, means for periodically moving said frame up and down about its axis, and means for intermittently rotating said turret through a complete circumference.

3. In a brush making machine, the combination of a movable frame, a support for holding a plurality of brush backs or the like movably mounted on said frame, means for periodically moving said frame up and down, means for intermittently moving said support longitudinally on the frame, means for intermittently rotating said support on its own axis, and means for simultaneously boring a hole in a brush back on one side of the support and setting a tuft of bristles in another brush back on the other side of the support.

4. In a brush making machine, the combination of a movable frame, a single rotary support for holding a plurality of brush backs or the like movably mounted on said frame, means for periodically moving said frame up and down, means for intermittently rotating the support through small arcs about its own axis, and means for intermittently moving said support longitudinally on the frame in a straight line.

5. In a brush making machine, the combination of a frame pivoted to swing on a horizontal axis, a turret for holding brush backs or the like movably mounted on said frame, means for periodically moving said frame up and down, and means for intermittently moving said turret longitudinally on the frame.

6. In a brush making machine, the combination of a frame pivoted on a horizontal axis, located at one side thereof and substantially on the same level, a brush supporting turret rotatably mounted thereon, a cam having a series of steps thereon, and means operated by said cam for swinging said frame up and down about said axis.

7. In a brush making machine, the combination of a frame pivoted to swing on a horizontal axis, a turret for holding brush backs or the like rotatably and movably mounted to the slide on said frame, means for periodically moving said frame up and down, a roll connected with the turret, means for giving the roll a step-by-step motion in a direction to move the turret intermittently in a longitudinal direction, a pawl having a recess for receiving the roll, a latch for holding said pawl, a spring tending to pull the pawl back, and means whereby when the roll enters the recess the pressure of the roll will move the pawl away from the latch to allow the roll to move back to its extreme position.

8. In a brush making machine, the combination of a frame pivoted to swing on a horizontal axis, a turret for holding brush backs or the like movably mounted on said frame, a cam having a substantially step by step spiral groove, a roll connected with the turret operating in said groove whereby the turret will be moved intermittently in a longitudinal direction, a pawl located at the outer end of said groove having a recess for receiving the roll, and means whereby the pressure of the roll will allow the roll to move into the low part of the cam groove.

9. In a brush making machine, the combination of a frame, a turret for holding brush backs or the like movably mounted on said frame, a cam having a groove therein, a roll connected with the turret operating in said groove whereby the turret will be moved in a longitudinal direction, a pawl located at the outer end of said groove for receiving the roll, a latch for holding said pawl in registration with the end of the groove, a spring tending to pull the pawl back out of the low part of the groove, and means whereby when the roll engages the pawl the pressure of the roll will move the pawl away from the latch to allow the roll to move into the low part of the cam groove, whereby the roll will be released from the pawl to allow the spring to operate and restore the pawl to its position behind the latch.

10. In a brush making machine, the combination of a drive shaft, an index clutch shaft, a gear loose on the index clutch shaft positively driven by the drive shaft, a clutch on the index clutch shaft adapted to transmit the rotation of said gear to the index clutch shaft, mechanism operated by the index clutch shaft for supporting and moving brush blanks, and means whereby the complete rotation of said index clutch shaft will automatically cause the clutch to be disengaged.

11. In a brush machine, the combination of a driving shaft, an index clutch shaft, means operated by the driving shaft for causing the index clutch shaft to rotate

throughout a complete revolution and then stop at the end of said revolution, a cam shaft, means for driving the cam shaft throughout a complete revolution and then 5 stopping, a wedge cam on said cam shaft, a turret having clamps thereon for holding brush blanks, a lever operated by said cam, and means connected with said lever for controlling the opening and closing of said 10 clamps.

12. In a brush machine, the combination of a driving shaft, an index clutch shaft, a gear loose on said latter shaft means for driving the gear from the driving shaft, 15 means for causing the index clutch shaft to be positively connected with said gear and to rotate throughout a complete revolution and then stop at the end of said revolution, a cam shaft, a gear loose on the cam shaft, 20 means for driving the last named gear positively, means for causing the last named gear to drive the cam shaft throughout a complete revolution and then stop, a wedge cam on said shaft, a turret having clamps 25 thereon for holding brush blanks, a lever operated by said cam, and means connected with said lever for controlling the opening and closing of said clamps.

13. In a brush making machine, the combination of a drive shaft, an index clutch shaft, means for driving the index clutch shaft positively from the drive shaft throughout exactly a complete revolution, said index clutch shaft being made in two 30 parts, having a universal joint between them, an oscillatable frame, means operated by the drive shaft for oscillating said frame bearings on said oscillatable frame for the second part of said index clutch shaft, and a 35 brush holding turret on said frame operated by the second part of the index clutch shaft.

14. In a brush making machine, a brush back turret, means for moving it, said turret having a plurality of stationary jaws thereon 40 and a corresponding number of movable jaws yieldingly pressed toward the stationary jaws, a longitudinally movable wedge located between each pair of jaws, means whereby when the wedge is moved in one 45 direction it will be forced outwardly to clamp a brush back in the jaws, and means on the jaws for holding a brush back in the side thereof, opposite the wedge.

15. In a brush making machine, a brush 50 back turret having a stationary jaw thereon, and a movable jaw yieldingly pressed toward the stationary jaw, each jaw having a lip for engaging beyond the surface of the brush back, a wedge located between the jaws, 55 means whereby when the wedge is moved in one direction it will be forced outwardly to clamp a brush back in the jaws, and means on said wedge for forcing the yielding jaw away from the movable jaw when the wedge 60

is drawn back, whereby the brush back will 65 be released.

16. In a brush making machine, the combination of a brush turret having a plurality of pairs of jaws thereon, a longitudinally movable rod, means for reciprocating the 70 rod, a slide operated by said rod, a wedge member between each of said pairs of jaws connected with and operated by said slide for simultaneously opening the jaws of two pairs to release or receive a brush blank, and 75 means whereby the jaws of the other pairs are kept closed during said releasing operation.

17. In a brush making machine, the combination of a turret having a plurality of 80 pairs of jaws thereon for gripping brush blanks, means for turning said turret, each pair of jaws having a wedge between the same for controlling the opening and closing of the jaws, a longitudinally movable rod, 85 means for reciprocating the rod, a slide at the end of said rod and provided with means for engaging simultaneously two of said wedges whereby the reciprocation of the rod will cause the said two wedges to reciprocate 90 for opening and closing said jaws.

18. In a brush making machine, the combination of a turret having a plurality of pairs of jaws thereon for gripping brush blanks, each pair of jaws having a wedge 95 between the same for controlling the opening and closing of the jaws, a longitudinally movable rod, a slide at the end of said rod provided with means for engaging two of said wedges whereby the reciprocation of the rod will cause the said wedges to reciprocate 100 for opening and closing said jaws, a shaft having a cam thereon provided with a cam groove which groove has a radial portion therein extending to the outer edge of 105 the cam, and a lever connected with said rod for reciprocating it having its end entering said groove whereby in one position of said cam said lever can move through said radial portion without being controlled by the cam, and means for rotating said cam shaft through a complete revolution to make a complete reciprocation of the rod and leaving the cam in position for the end of the lever to register with said radial portion of 110 the groove.

19. In a brush machine, the combination with a turret having a brush clamp thereon, of a hopper for brush blanks located adjacent to said turret, means for moving said hopper bodily forward into position to deliver a blank to a clamp on the turret, and means for delivering a blank from the hopper to the turret while the hopper is forward. 120

20. In a brush machine, the combination of a turret for receiving blanks, a hopper movable into position for delivering blanks to the turret, said hopper being constructed 125

and adapted to hold brush blanks piled one upon another, having a plunger for forcing a brush blank out of the hopper, and being provided with a latch at the delivery end 5 of the hopper for normally projecting under a lower blank and holding it up.

21. A supply hopper for a brush making machine, having means for holding a plurality of blanks one upon another, in combination with a plunger having a pusher adapted to engage an end of the blank located at the bottom of the hopper, means for receiving the end of the blank nearest the pusher and supporting that end, and a latch 15 adapted to project under the other end of a blank and hold it in position when the pusher is at one extreme end of its stroke and adapted to move away to permit that 20 end of the blank to drop when the pusher moves from that position.

22. A hopper for a brush making machine, comprising means for supporting a pile of brush blanks, a pusher for engaging the bottom blank in the hopper, a latch at the 25 other end of the hopper for projecting under the bottom of a blank at that end, a spring for normally moving said latch away from the blank, and means connected with said 30 pusher for positively forcing said latch into its holding position when the pusher is withdrawn to the extreme end of its stroke.

23. In a brush making machine, the combination of a hopper for supporting a pile of brush blanks, a pusher for engaging the bottom blank in the hopper and pushing it forward, a latch at the other end of the hopper for projecting under the bottom of a blank at that end, a spring for normally 35 moving said latch away from the blank, 40 means connected with said pusher for positively forcing said latch into its holding position when the pusher is withdrawn to the

extreme end of its stroke, a turret located under the hopper, a gear wheel for rotating said turret, a series of jaws carried by the 45 turret for receiving brush blanks from the hopper, and a series of adjustable stops carried by the gear wheel for limiting the position of each brush blank delivered thereto.

24. In a brush making machine, the combination of a hopper for supporting a pile of brush blanks, a pusher for engaging the bottom blank in the bottom and pushing it forward, a turret located under the hopper, a wheel for rotating said turret, a series of 50 55 jaws carried by the turret for receiving brush blanks from the hopper, and a series of adjustable stops carried by the wheel for limiting the position of each brush blank delivered thereto.

25. In a brush machine, the combination of a turret having jaws thereon for carrying brush blanks, a slide mounted adjacent to the turret, a hook pivoted on said slide for engaging a brush blank, and means for moving said hook into engagement with the end of a brush blank on the turret and for then moving the slide to slide the brush blank out of the turret.

26. In a brush machine, the combination 70 of jaws for carrying brush blanks, a slide, a hook pivoted on said slide for engaging a brush blank, means for moving said hook into engagement with the end of a brush blank and for then moving the slide to slide 75 the brush blank out, and means to release the brush blank so that when the hook engages the end of the brush blank the brush blank will be freed so that it can be removed from said jaws.

In testimony whereof I have hereunto affixed my signature.

ARTHUR W. LE BOEUF.
